WASTE GUARD

William E. Myers, Louisville, Ky.

Application September 16, 1946, Serial No. 697,331

2 Claims. (Cl. 308—89)

1

My invention relates to a guard more especially intended for use in the journal boxes of railway cars and has for its object the provision of means whereby the lubricant conveying waste employed in journal boxes will be prevented from creeping up on the journals during revolution of the latter and becoming lodged between the journals and the journal bearings.

The invention also has for its object the provision of means adapted to provide a comb effect whereby the strands of the lubricant saturated waste material in the journal box, or any other solid substance, will be combed from the revolving journal at a distance removed from the journal bearing or brass without, however, interfering with or preventing adherence of the desired or necessary film of oil to the journal; my improved device causing the accumulated combings as well as excess lubricant to drop down into the oil and waste holding cellar or well of the journal box.

My improved device contemplates a pair of resiliently held comb-like portions constructed to effect a constant steady pressure against the journal sufficient to remove adhering strands of the waste but insufficient to break or interrupt the oil film on the journal.

A further object of the invention is the provision of a guard which will not interfere with the normal packing operation of the journal box and which will be so positioned as not to be subject to damage by the usual packing irons employed; the structure being such that it may be easily applied and readily removed from the journal box when occasion requires.

The foregoing objects and advantages, as well as other advantages inherent in my invention, will all be readily comprehended from the detailed description of the accompanying drawings wherein—

Figure 1 is a perspective view of my improved waste guard.

Figure 2 is a partial vertical section and end elevation of journal and journal box with the box cover or lid removed, illustrating application of my improved waste guard.

Figure 3 is a longitudinal sectional plan of one-half of a journal and journal box and one side or half of my applied guard.

Figure 4 is a vertical sectional view of a journal, journal box and bearings in possible relationship during certain running conditions, with my improved guard applied.

Although my invention may be used in connection with the bearing box of any rotating element

2

or shaft which employs lubricant absorbing fibrous material, it is especially adapted for use with the conventional journal boxes employed in railroad car construction wherein the lower part or well of the journal box is filled with a lubricant absorbing fibrous material or waste arranged in contact with the lower part of the journal to apply the lubricant or oil to the journal during its rotation. During the rapid rotation of the journal particles of this packing or strands of the fibrous waste frequently adhere to the journal and are carried beneath the journal bearing or brass, arranged in contact with the upper or car-weight supporting side of the journal; a condition which produces hot journals and is a prevalent cause of hot boxes.

My invention is designed to eliminate the difficulties mentioned and in the specific exemplification of the invention consists preferably of two similar elongated and serrated elements or comb-like members 10, 10 preferably of triangular cross-section and the base or journal opposing side of each member provided with a longitudinal groove or channel 11 extending throughout the length of the member and the diverging marginal portions of each member on opposite sides of the channel 11 serrated to provide the vertically spaced series or rows of comb-like, blunt-ended, teeth 12 on each member 10. That is to say, the two rows of teeth 12 on each member 10 are arranged in flaring relation so as to conform with the circumferential curvature of the journal; and the members 10 preferably are made to taper somewhat longitudinally toward what may be termed their inner non-attached ends, with the distal or free ends on their serrated sides slightly curved or flared outwardly as at 13 and shown in Figure 1, to conform with the usual curved shoulder at the inner end of the journal.

The body portions or comb-like members 10, 10 are made of any suitable journal non-cutting or non-scoring and wear resisting material, such as a moldable plastic material of a heat, moisture and lubricant resisting nature.

The two brushes or comb-like members 10, 10 are secured together and yieldingly held in predetermined laterally spaced relation by the ball or spring steel looped wire 14, whose ends preferably are molded or embedded in the body members 10 as shown in dotted lines at 15 in Figure 1, with the intermediate portion extending upward through the upper surface adjacent the outer large end of each member 10 as shown at 16 and thence bowed laterally and slightly outward from the vertical plane of the outer ends of

the body members 16, 18; the intermediate portion being bent into the arcuate form shown at 17, so as to extend above and out of contact with the journal 18 as shown in Figure 2.

The ball members 14 must be of a resilient material, such as flexible tempered spring steel wire, whereby each brush or comb-like member 16 will exert a steady or constant pressure—for example a pressure of approximately four pounds per brush or comb member—against the sides of the journal 18. That is to say, the connecting or ball member 14 should be of such flexible and spring-like formation as to yieldingly urge the brush or comb-like members 16 toward each other with sufficient pressure to maintain the members 16 in constant contact with opposite sides of the journal and prevent packing strands from adhering to the rotating journal and becoming wedged beneath the journal bearing and brass shown at 18, 20 in Figure 2.

The pressure of the comb-like members, however, is intended to be such as not to disturb or break the oil film on the journal in its passage upwardly to the brass; the resilient ball 14 being adapted to extend slightly over the collar or flange 24 at the outer end of the journal and thereby, in conjunction with its resiliency, position the guard and maintain it above the transverse center of the journal 18, as shown in Figures 2 and 4.

As clearly shown in Figure 2, the formation of the comb-like members 16, 18 and their rigid connection to the ball member 14 are such that both toothed longitudinal edges of the members 16 are held in contact with the journal during normal running conditions and minimum journal wear; while Figure 4 illustrates the guard position during possible relative relation between journal and journal box and with maximum wear on the journal, at which time the lower row of teeth 12, at least, will contact or be in combing relation with the journal.

Each comb member 16 at its outer end and outer tapered side is provided with a triangular enlargement or lug 22; these lugs 22 being adapted to also assist in maintaining the proper relation between the combing portions of the guard and the journal; the triangular formation or upper sloping sides of the sections 16 and of the lugs 22 permit the comb-sections to extend substantially parallel with the lower longitudinal marginal portion of the journal bearing member 18 and the lugs to have flat bearing relation with the shoulders in the side walls of the journal box, as shown at 23 in Figures 2 and 4.

With my improved guard any strands or particles of the lubricant saturated and conveying waste (which is located in the well or bottom of the journal box as shown at 24) which may adhere to or be entrained by the rapidly rotating journal will be combed off the journal by the teeth 12, especially by the lower row of teeth, and prevented from further traveling upwardly on the journal and beneath the bearing brass where the waste fibers and any entrained grit frequently result in cut or scored journals and cause "hot box" conditions.

The serrated or toothed formation of the body members 16, 18, in addition to intercepting and combing the adhering waste strands from the journal without wiping the desired oil film off the journal, causes the combed mass to drop to the lower or lubricant holding well of the journal box; the interstices in the members 16, 18 permitting the excess lubricant particles or oil to

trickle down into the lubricant holding well. As a result, the journal is wiped clean of grit and any solid substance while proper lubrication at all times is ensured and hence the average life of the journal bearings is materially increased. That is to say, my improved waste guard is designed to eliminate the expense and loss of time due to hot box car operation, delay in train operations, and the costly operation of changing car wheels necessitated by badly scored or cut journals.

My improved guard by reason of its construction and flexibility of the body holding spring or ball may be easily applied or removed should occasion require; and is designed not to interfere with the normal packing of the journal box, being so positioned above the normal packing level and the packing operation zone that it is not subject to damage by the packing irons generally employed in inspection and waste renewal operations; the ball or body holding spring of the guard being so formed as not to interfere with the proper closing of the journal box cover or lid.

The exemplification shown and described is believed to be the simplest and best embodiment of the invention, but structural modifications may be possible without, however, departing from the spirit of my invention as defined in the appended claims.

What I claim is:

1. A waste guard for the journal of a railroad car axle comprising a unitary structure composed of a rigid spring steel U-shape frame having elongated sides or legs and an intermediate loop portion offset into a plane above the plane of the sides or legs so as to fit across the top of the journal collar and a journal side engaging elongated comb-like body portion of non-metallic material moulded on each frame side or leg of V-shape cross section with the flared side disposed toward the journal and transversely slotted throughout its length to provide vertically spaced rows of teeth having blunt ended vertically tapered ends conforming to the curvature of the journal.

2. A waste guard for the journal of a railroad car axle comprising a unitary structure composed of a rigid spring steel U-shape frame having spaced elongated sides or legs united at one of their ends by a vertically off-set loop adapted to fit across the top and beyond the end of the journal and formed to flex the sides or legs toward each other, and a journal side engaging body portion of non-metallic heat and lubricant resisting material moulded on and throughout the length of each frame side or leg of V-shape cross-section to provide a pair of vertically spaced journal engaging portions tapering toward the free end of the leg, with the flared side disposed toward the journal and transversely slotted to provide vertically spaced rows of teeth having ends conforming to the curvature of the journal.
